UNITED STATES PATENT OFFICE.

ROBERT ALEXANDER MOORE, OF NEW YORK, N. Y., ASSIGNOR OF ONE-SIXTH TO
GEORGE M. BEERS, ONE-SIXTH TO WILLIAM E. LOWN, AND ONE-SIXTH TO FLOYD
B. WILSON, ALL OF NEW YORK, N. Y.

PROJECTILE.

1,176,082.

Specification of Letters Patent. Patented Mar. 21, 1916.

Application filed December 15, 1914. Serial No. 877,312.

To all whom it may concern:

Be it known that I, ROBERT ALEXANDER MOORE, a citizen of the United States, residing at New York, in the county of New York and State of New York, have invented certain new and useful Improvements in Projectiles, of which the following is a specification.

The primary purpose of this invention 10 has been to produce a new type of projectile especially designed for use in connection with large caliber guns or rifles constituting what is generally known as heavy ordnance.

In the carrying out of the invention I 15 have employed as essential parts of my projectile construction a body or core preferably though not necessarily solid in form, the same being surrounded and entirely inclosed by a shell capable of rotation thereon.

20 As an essential feature of my invention I contemplate the formation of the body of the projectile and the casing or inclosing shell therefor, in such a manner that these parts are spaced from one another reducing 25 the friction between the same to a minimum and facilitating the rotation of the shell.

My invention includes also, broadly, the provision of a projectile body with a surrounding shell or casing spaced therefrom, 30 and a liquid filling the space intermediate said parts, said liquid being preferably oil or water. Subsidiary to the foregoing is the employment of the same parts with the interposed liquid contained therebetween, 35 and the shell capable of rotation about the body or core.

Still another feature of the invention resides in the provision of a peculiar formation of point for the projectile, facilitating 40 its rotation when projected into space; also the provision of a special formation of butt end for the projectile designed in such a way as to peculiarly confine the gases of the explosion utilized to fire the implement 45 of war whereby the power of said gases may be concentrated to produce the greatest possible projecting effect upon the projectile.

Having in view the foregoing objects, I, therefore, do not wish to be limited to the 50 special construction of my invention as is hereinafter presented in detail, and as fully shown in the accompanying drawings, wherein—

Figure 1 is a side view of a projectile

embodimenting the essential features of said invention. Fig. 2 is a vertical longitudinal sectional view of the same on the line 2—2 of Fig. 1.

My projectile is comparatively simple in its structure comprising as it does the outer shell or casing 1 pointed or tapered at one end. The said shell 1 incloses the body or core 2 illustrated as solid and spaced from the shell as shown at 3. Intermediate the front end portions of the body 2 and the shell 1 are the ball bearings 4 and 5 which operate in suitable recesses formed in the respective parts.

I preferably so form the body 2 that spindles 6 and 6' project from the ends of said body, the ball bearings 5 being interposed between the walls of a socket in the extremity of the shell 1, and said spindle 6, and other ball bearings 7 between the walls of the other socket of the shell and the spindle 75 6'. The rear end of the spindle 6' terminates short of the rear end of the socket receiving the same leaving a space seen clearly in Fig. 2.

In brief, it will be apparent from the foregoing that the shell 1 is capable of rotating on the body 2 there being antifriction bearings between the parts. The rear end wall of the chamber, which is formed through the fact that the shell 1 is hollow, 85 is provided with a number of concentric grooves 3' constituting liquid chambers in the same manner that the space 3 constitutes a corresponding chamber for oil, water, or the like.

90 The butt 8 of the projectile constitutes an integral extension of the shell 1 and is formed with the annular concavities 9 and 10 as well as a rearmost round projection 8'. The concavities 9 and 10 are such that 95 on the explosion of the charge by which the projectile will be fired from a gun the gases generated will be caused to rush into the concavities and being directed toward the longitudinal central axis of the projectile 100 will produce a maximum effect so far as projecting power is concerned to carry the projectile the greatest possible distance.

105 The interposition of the oil or water between the shell 1 and the body 2 of the projectile is advantageous in facilitating not only the rotation of the shell 1 on the body but in affording an insulation film reducing

the heating of the barrel of the gun or rifle incident to the passage of the projectile therethrough.

The rotation of the shell 1 will be caused by the usual rifling of the gun or weapon and also through the provision of the spiral grooves or recesses 11 at the point of the projectile, the curvature of the latter being such that the tendency of the air resistance to the progress of the projectile through space is to effect a revolving movement of the shell 1 about the body 2. Since the rear end of the body 2 abuts with the rear end wall of the chamber in which said body is inclosed no strain and consequent distortion of the bearings 4 and 5 and 7 is likely to be created by the sudden movement of the projectile when fired from a weapon.

Having thus described my invention, what I claim as new is:

1. A projectile comprising in combination a solid body, a rotatable shell surrounding the body in spaced relation thereto, bearings intermediate said parts permitting rotation of the shell on the body, and a film of liquid intermediate the shell and body and consisting of a body of oil for lubricating the bearings and acting as an insulating barrier.

2. A projectile comprising a body, a shell wholly inclosing said body and formed with a penetrating point and a butt at the other end, bearings intermediate said shell and body spacing the same apart at the sides thereof, the shell being provided with a liquid film intermediate the same and the body at the sides of the latter and intermediate said parts at their rear-ends, said shell having its rear inner wall formed with concentric grooves forming lubricant races for facilitating rotation of the shell.

3. A projectile provided with a penetrating point at one end and a butt at the opposite end, said butt being formed with con-

centric annular concavities, the surface of the butt portion being convex adjacent to the concavities whereby to concentrate propelling gases acting on the projectile toward the central longitudinal axis of said projectile.

4. A projectile comprising a body, a shell rotatable about said body, the shell being formed with spiral grooves adjacent to its point for imparting rotation to the shell upon projection from a gun, and a liquid lubricant disposed intermediate the body and the shell for facilitating rotation of the shell under actuation by the grooves aforesaid, said lubricant constituting an insulating film substantially as set forth.

5. A projectile comprising a body, a shell rotatable about said body, means on said shell for imparting rotation thereto after the projectile is discharged from a gun, and a liquid film interposed between the shell and body for facilitating rotation of the former.

6. A projectile comprising a body of solid penetrating material, a shell rotatable on said body, means on said shell at one end for imparting rotation thereto, and means at its other end for concentrating the gases acting upon said end in the discharge of the projectile toward the central longitudinal axis of said projectile and substantially eliminating suction or vacuum from the rear of the projectile while in flight, said means consisting of annular grooves cut into the shell in a direction forwardly of its longitudinal axis, the surface contiguous to the grooves rounding outwardly thereby forming reverse curves.

In testimony whereof I affix my signature in presence of two witnesses.

ROBERT ALEXANDER MOORE.
